Primary Examiner — Wan Laymon(57) **CLAIM**

The ornamental design for a gel ice hat, as shown and described.

DESCRIPTION

FIG. 1 is a front and top perspective view of a gel ice hat, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in a using position; and,

FIG. 10 is an enlarged perspective view of detail "10" identified in FIG. 2.

The broken lines showing of a person in FIG. 9 depict environmental structure that form no part of the claimed design. The dash dot dash lines in FIGS. 2 and 10 are for the purpose of illustrating the enlarged view indicators and form no part of the claimed design.
